UNITED STATES PATENT OFFICE.

FRANK O. HELLSTROM, OF GROVE, NORTH DAKOTA.

RAIL-SUPPORT.

1,112,613.

Specification of Letters Patent.

Patented Oct. 6, 1914.

Application filed February 18, 1914. Serial No. 819,448.

To all whom it may concern:

Be it known that I, FRANK O. HELLSTROM, a citizen of the United States, residing at Grove, in the county of Burleigh and State 5 of North Dakota, have invented a new and useful Rail-Support, of which the following is a specification.

This invention relates to rail supports or stringers, one of the objects being to provide 10 a composite structure made up of a plastic filling, a metal sheathing, and a cushioning element whereby a heavy durable structure is obtained and the rail is provided with a continuous cushioning support which allows 15 ties to be completely dispensed with.

A further object is to provide a rail support or stringer the sheathing and cushioning members of which form a mold for retaining the plastic filling during the 20 construction of the stringer so that the cost of producing the stringer is reduced to the minimum.

A further object is to provide simple 25 means whereby the sides of the sheathing are securely tied together and additional means for anchoring said sides to the plastic filling.

A further object is to provide improved 30 means for connecting opposed stringers or supports.

A further object is to provide a casing 35 which constitutes means for preventing lateral displacement of the rails, the tie devices employed for connecting the rail supports or stringers being formed with integral rail retaining means so that it becomes unnecessary to employ spikes or similar fastening devices.

With the foregoing and other objects in 40 view which will appear as the description proceeds, the invention resides in the combination and arrangement of parts and in the details of construction hereinafter described and claimed, it being understood that 45 changes in the precise embodiment of the invention herein disclosed, can be made within the scope of what is claimed, without departing from the spirit of the invention.

In the accompanying drawings the preferred 50 form of the invention has been shown.

In said drawings: Figure 1 is a perspective view of portions of opposed rail supports or stringers, the rails being shown in position thereon. Fig. 2 is an enlarged 55 transverse section through one of the rail supports and the rail thereon. Fig. 3 is an

elevation of one of the rail retaining plates. Fig. 4 is a transverse section through one of the tie strips and showing the upstanding end portion thereof. Fig. 5 is an enlarged 60 section through a portion of the casing and showing the reinforcing and anchoring strip thereunder.

Referring to the figures by characters of reference 1 designates an outer casing strip formed of sheet metal, this strip being provided with an upstanding flange 2 along its upper or inner edge. The strip 1 is inclined downwardly and laterally away from the flange 2 and merges into an upstanding wall 3 from which projects an inwardly extending flange 4. An angle strip 5 constituting a combined reinforcing and anchoring means is riveted or otherwise secured to the lower surface of the inclined portion of the strip 1 70 and extends longitudinally of the strip. 75

The inner casing strip 6 is similar to the strip 1 and includes a downwardly and laterally inclined portion along the upper edge of which is provided an upstanding longitudinal flange 7 while the lower part of said inclined portion merges into a vertical wall 8 having an inwardly extending longitudinal flange 9. An angle strip 10 constituting combined anchoring and reinforcing means, 80 is riveted or otherwise secured to the bottom of the inclined portion 6 and extends longitudinally thereof forming an inverted V-shaped saddle over the underlying plastic substance. 85

A cushioning block 11 of wood or the like is interposed between the flanges 2 and 7 but does not extend to the upper edges of the flanges. Consequently a seat is formed upon the block 11 and between the upper edge portions of the flanges 2 and 7 for the reception of the rails R, the said flanges 2 and 7 constituting means for preventing the rails from shifting laterally off of the block 11. 90

Bolts 12 are extended inwardly from the vertical wall 3 and terminate in hooks 13 for engaging the inner ends of eye bolt 14, the outer ends of these eye bolts being held to the vertical walls 8 in any suitable manner. 100 When the bolts 12 and 14 are in engagement with each other, they prevent the casing members from moving apart at their bases. 105

For the purpose of securing the cushioning blocks 11 between the flanges 2 and 7, 110 bolts 15 are extended transversely through the blocks and also through the flanges 2

and 7, these bolts being preferably formed with the usual oval portions 16 for preventing rotation thereof. One end of each bolt engages the upstanding portion 17 of a rail retaining plate, this plate having a downwardly and laterally inclined tongue 18 and an inwardly extending rail engaging lip 19. Said lip is adapted to extend over the flange 2 and to lap the outer base flange 10 of the rail R, as shown particularly in Fig. 2. Tongue 18 is engaged by a bolt 20 which extends through the strip 1 and into a nut 21 seated under the plate 1. This nut can be of any suitable type, either the ordinary one piece nut, or it can be an expansion nut of the usual type.

Arranged along the plate 6 at desired intervals are tie straps 22 having upwardly and outwardly inclined portions 23 adapted 20 to rest snugly upon the inclined portion of the plate 6 and to be secured thereto by means of bolts 24 which extend through the plate 6 and the reinforcing strip 10 and into engagement with a nut 25 which can be of the usual one piece form or can be an expansion nut of the usual type. Each inclined portion 23 merges into an upwardly extending portion 26 having a rail retaining lip 27 at its upper end adapted to extend 30 over the flange 7 and to lap the inner base flange of the rail R. The bolt 15 extends through the flange 7 and the upstanding portion 26 and it will be apparent that when a nut 28 is tightened on the bolt 15, the flanges 35 2 and 7 will be clamped tightly upon the block 11 while the rail engaging lips 19 and 27 will be brought into intimate engagement with the base flanges of the rail R.

All of the space between the plates 1 and 40 6 and below the blocks 11 is filled with a plastic material 29, preferably concrete, the bolts 12 and 14 being anchored within this filling and being held thereby against separation while the filling is furthermore anchored tightly in the casing made up of plates 1 and 6 by the flanges 4 and 9, the bolts 12 and 14, and the reinforcing and anchoring strips 5 and 10. It has been found that the structure can be readily made by 45 assembling the parts 1 and 6 in inverted positions, placing the cushioning blocks 11 between the flanges 2 and 7 and then, after filling the ends of the spaces between the plates 1 and 6 with blocks or heads not 50 shown, pouring the concrete into the mold thus produced and allowing it to set and harden. The structure can then be reversed so as to bring the exposed flat surface of the plastic filling lowermost whereupon the 55 stringer or rail support is ready for use.

It will be seen that the structure herein described provides a heavy and durable support for the rails and obviates the necessity of utilizing the ordinary cross ties such as 60 commonly employed. Furthermore it be-

comes unnecessary to employ spikes or similar fastening devices, in view of the fact that the particular rail fastening means disclosed are used. The blocks 11 afford ample cushioning means for the rails and as the rails are provided with continuous unbroken supports, there is no danger of said rails 70 breaking or causing the wheels to pound.

What is claimed is:—

1. A rail support including opposed casing members having spaced inwardly directed bottom portions, upwardly extending rail retaining portions, tie devices, and a plastic filling anchored between the casing portions and adapted to engage the road bed. 75

2. A rail support including opposed casing members having spaced inwardly extending bottom portions, and upwardly extending rail retaining portions, and a plastic material anchored between the casing members and completely filling the space therebetween and below the upwardly extending rail engaging portions said filling being adapted to bear downwardly upon the road bed. 80

3. A rail support including opposed casing members having inwardly extending bottom portions and upwardly extending rail retaining portions, means connecting the casing members adjacent their bottoms for holding them against spreading, a plastic filling interposed between the members and anchored by said connecting means, a cushioning element interposed between the upwardly extending rail engaging portions and bearing upon the plastic material. 85

4. A rail support including opposed casing members having inwardly extending bottom portions and upwardly extending rail retaining portions, means connecting the casing members adjacent their bottoms for holding them against spreading, a plastic filling interposed between the members and anchored by said connecting means, a cushioning element interposed between the upwardly extending rail engaging portions and bearing upon the plastic material, said rail engaging portions being extended upwardly above the cushioning member, and means 95 extending transversely through the cushioning member and the upwardly extending rail engaging portions for holding said member and rail engaging portions together. 100

5. A rail support including opposed casing members having inwardly extending bottom portions and upwardly extending rail retaining portions, means connecting the casing members adjacent their bottoms for holding them against spreading, a plastic filling interposed between the members and anchored by said connecting means, a cushioning element interposed between the upwardly extending rail engaging portions and bearing upon the plastic material, said rail engaging portions 110

- being extended upwardly above the cushioning member, means extending transversely through the cushioning member and the upstanding rail engaging portions for holding said member and rail engaging portions together, and rail fastening devices engaged and held by said means.
6. A rail support including opposed casting members constituting the sides of the support and having upwardly extending continuous rail retaining flanges, a plastic material having all portions embraced between the casing members and anchored thereto, and a cushioning element interposed between the flanges and bearing upon the plastic material.
7. A rail support including opposed casting members constituting the sides of the support and a plastic filling having all portions embraced and anchored therebetween, a cushioning block bearing downwardly on the filling and interposed between the flanges, said flanges extending above the block.
8. A rail support including opposed casting members constituting the sides of the support and a plastic filling having all portions embraced and anchored therebetween, a cushioning block bearing downwardly on the filling and interposed between the flanges, said flanges extending above the block, and rail fastening devices secured to the flanges and extending inwardly therebeyond.
9. A rail support including opposed casting members having upwardly extending continuous rail retaining flanges, angular reinforcing strips secured to the lower faces of the members, a plastic filling interposed between the members and anchored thereto
- by the strips, a cushioning block interposed between the flanges, said flanges extending upwardly above the block.
10. A rail support including opposed casting members having upwardly extending continuous rail retaining flanges, angular reinforcing strips secured to the lower faces of the members, a plastic filling interposed between the members and anchored thereto by the strips, tie bolts connecting the members and embedded within a filling.
11. A rail support including opposed casting members having upwardly extending continuous rail retaining flanges, angular reinforcing strips secured to the lower faces of the members, a plastic filling interposed between the members and anchored thereto by the strips, tie bolts connecting the members and embedded within a filling, and a cushioning block supported by the filling and interposed between the flanges.
12. The combination with opposed rail supports, each including a metal casing, a plastic filling anchored therebetween, and means upstanding from the casing for engaging the base of a rail to prevent lateral displacement of the rail, of a tie element, means for securing said element to the opposed supports, and rail retaining means formed by the terminals of said element and lapping the base flanges of rails carried by the respective supports.

In testimony that I claim the foregoing as my own, I have hereto affixed my signature in the presence of two witnesses.
